UNITED STATES PATENT OFFICE.

JOSEPH MARIE ETIENNE FRANC, OF LYON, FRANCE.

VEHICLE-SPRING.

1,273,761.

Specification of Letters Patent. Patented July 23, 1918.

Application filed December 15, 1916. Serial No. 137,106.

To all whom it may concern:

Be it known that I, JOSEPH MARIE ETIENNE FRANC, a citizen of the French Republic, residing at Lyon, in France, have invented 5 certain new and useful Improvements in Vehicle-Springs, of which the following is a specification.

This invention relates to improvements in vehicle springs more especially applicable to 10 motor cars.

The device comprises a leaf-spring connected to the chassis of the vehicle by means of a support on which it can oscillate freely. Combined with this leaf spring is a spiral 15 spring, set in action by said leaf-spring, and connected at one end to an arm connected to the coupling member of the plates of the leaf-spring and at the other end to a double armed lever, provided with a lateral arm 20 connected by a link to a pivot around which is rolled the main leaf of the leaf spring, while the second arm of the lever which is in extension of the first is connected to the chassis.

25 The annexed drawings illustrate the invention.

Figure 1 is an elevation of the improved vehicle spring.

Fig. 2 is a section on the dotted line in 30 Fig. 1.

The device is essentially composed of a leaf-spring *a* secured to the coupling plate *a'* and eye block *c* by straps *b* provided with nuts *b'*, the coupling plate being situated 35 not in the middle of the leaf spring but at about one third of its length from the front end thereof. The eye block *c* rocks on a bolt *d'* projecting from a bracket *l* secured to the chassis frame. The eye block *c* has a down- 40 wardly extending arm *d* having at its end an eye *e* to receive a screw threaded rod *f*, regulatable in length, by means of the nut *g*; to this rod is attached a spiral spring *h* the other end of which is fixed to a member 45 *i* surrounding and sliding on a lever *j* provided at right angles with an arm *k* to which is pivoted as at *l* a link *m* provided with a pivot *n* around which is rolled the main leaf *o* of the leaf-spring *a*.

50 The fulcrum of the lever *j*, *k* is connected by a link *p* pivoted at *q* on the chassis frame *r* of the car. The main leaf is connected at the other end to the rear axle of the vehicle as at *s*.

55 The tension of the spiral spring *h* is regulatable by means of the nut *g* and rod *f*

and is also regulatable by sliding the member *i* along the lever *j* by means of a screw *t* engaging a screw threaded hole in said member so that the position of the hook or point 60 of attachment *v* of the spring to the lever *j* can be adjusted according to the weight of the car. The screw *t* revolves without end-wise movement in a bridge *2* and is provided with a hexagonal head *u*.

Owing to this arrangement the spring *h* acts as a compensating or check spring.

What I claim as my invention and desire to secure my Letters Patent of the United States is:—

1. A vehicle spring comprising in combination a leaf spring, a coupling plate therefor, situated at about one third the length of said leaf spring, means for attaching said coupling plate to said leaf spring, a support 75 for said coupling plate, a depending lever pivoted on said plate, a double armed lever having one end pivoted to the car frame, a pivot for said double armed lever, a lateral arm on said double armed lever, a link connecting the extremity of said lateral arm to the short end of said leaf spring with respect to said coupling plate, the long end of said leaf spring being connected to the vehicle axle and a traction spring connecting the extremity of said depending lever to the free end of said double armed lever. 80

2. A vehicle spring comprising in combination a leaf spring, a coupling plate therefor, situated at about one third the length of said leaf spring, means for attaching said coupling plate to said leaf spring, a support for said coupling plate, a depending lever pivoted on said support, a double armed lever having one end pivoted to the car frame, a pivot for said double armed lever, a lateral arm on said double armed lever, a link connecting the extremity of said lateral arm to the short end of said leaf spring with respect to said coupling plate, the long end of said leaf spring being connected to the vehicle axle, a traction spring connecting the extremity of said depending lever to the free end of said double armed lever and means for adjusting the 95 tension of said traction spring. 100

3. A vehicle spring comprising in combination a leaf spring, a coupling plate therefor, situated at about one third the length of said leaf spring, means for attaching said coupling plate to said leaf spring, a support 110 for said coupling plate, a depending lever

pivoted on said support, a double armed lever having one end pivoted to the car frame, an axle for said double armed lever, a lateral arm on said double armed lever, a 5 link connecting the extremity of said lateral arm to the short end of said leaf spring with respect to said coupling plate, the long end of said leaf spring being connected to the vehicle axle, a block slidable on the free 10 end of said double armed lever, means for sliding and fixing said block on said free end, a spiral spring having one extremity connected to said slidable block, a screw threaded rod passing through an eye of the 15 aforesaid depending lever and to which the other extremity of said spiral spring is connected, and a nut for adjusting the projection of said rod through said eye.

4. A vehicle spring comprising in combination a leaf spring, an eye block, means for attaching said eye block to said leaf spring, a bolt on which said eye block pivots, a depending arm on said eye block, a double 20 armed lever having one end linked to the car frame, a link connecting the extremity of one arm of the lever to one end of said leaf spring and a traction spring connecting the other arm of the lever to the eye block arm.

30 5. A vehicle spring comprising in combination a leaf spring, a coupling plate and eye block therefor, situated at about one third the length of said leaf spring, means for attaching said coupling plate and eye block to said leaf spring, a bolt on which 35 said eye block pivots, a depending arm on

said eye block, a double armed lever, a link connecting the fulcrum of the double armed lever to the car frame, a link connecting one of the arms of said lever to the end of 40 said leaf spring nearer to the coupling plate the end of said leaf spring remote from the coupling plate being connected to the vehicle axle, a traction spring connecting the said eye bolt arm to the other arm of said double armed lever and means for adjusting the tension of said traction spring.

6. A vehicle spring comprising in combination a leaf spring, an eye block therefor, means for attaching said eye block to said leaf spring, a bolt on which said eye block pivots, a depending arm integral with said eye bolt, a double armed lever, a link connecting the fulcrum of the double arm lever to the car frame, a link connecting the extremity of one of the arms of said lever to the end of said leaf spring, a sleeve slidable on the other arm of said double armed lever, means for sliding and fixing said block longitudinally of said arm, a spiral spring having one extremity connected to said eye bolt arm by a screw threaded rod passing through an eye of the aforesaid depending eye bolt arm, the other extremity of said spiral spring being connected to said sleeve.

In witness whereof I have signed this specification in the presence of two witnesses.

JOSEPH MARIE ETIENNE FRANC.
